REMOVABLE LAMP SHADE HAVING SLIDE
FASTENER SECURING MEANS

Katherine A. Stroschein, Arverne, N. Y.

Application May 10, 1950, Serial No. 161,240

2 Claims. (Cl. 240—108)

1

The present invention relates to improvements in a removable lamp shade having slide fastener securing means and has for an object the provision of a device of this kind in which the cover for the lamp shade frame is capable of being quickly and easily removed and replaced.

Another object of the present invention is to provide an improved lamp shade in which the spider or brace portion of the lamp shade frame is adapted to be removed so that the cover can be slipped on and off over the rings of the frame.

A further object of the present invention is to provide an improved structure which permits of performing with a sewing machine of all the necessary sewing on the cover before attaching to the frame.

A still further object of the present invention is to provide a device of this character which permits the cover to be applied to and removed from the frame repeatedly without mutilating the cover or the frame.

A detachable cover of this type is very desirable, especially where the cover is made of expensive textile material since it will permit the cover to be removed from the frame and cleaned or washed and then replaced on the frame.

A supply of these improved covers of various designs and color schemes can be kept in the house or store in flat condition so that the covers on the lamp shades can be changed as frequently as desired to impart to a room any desired motif in color or design.

With the foregoing and other objects in view, the invention will be hereinafter more fully described and more particularly pointed out in the appended claims.

In the drawings, in which the same parts are denoted by the same reference numerals throughout the several views,

Figure 1 is a perspective view of an improved complete lamp shade constructed in accordance with the present invention.

Figure 2 is a perspective view of the improved lamp shade frame with the cover removed.

Figure 3 is a fragmentary plan view of the improved lamp shade cover in flat form.

Figure 4 is a vertical sectional view of the complete assembled lamp shade, and

Figure 5 is an enlarged detail view of one of the hanger arms and its connection to the upper ring of the frame with parts broken away and in section.

Referring more particularly to the drawings, A generally designates a lamp shade frame which comprises a lower or base ring 10, an upper ring

11, vertical connecting bars 12 having their opposite end portions secured to the rings 10 and 11 by welding or the like and a hanger or spider generally indicated at B. The hanger comprises a ring or hub 13 from which radiate arms 14 the inner ends of which are secured as by welding or the like to the hub 13. The outer free end portion of each arm 14 is bent upwardly and inwardly to form a hook 15 as is shown in Figures 4 and 5 of the drawing. Any number of arms 14 could be provided but in the present illustration three such arms are shown which are disposed at substantially 120 degrees apart. Three brackets, generally indicated at C, are provided for supporting the hanger B. The brackets C are mounted on the upper ring 11 at points which are spaced apart substantially 120 degrees and each bracket is of substantially angle iron formation in cross section and comprises a vertical flange 16 and a horizontal flange 17. The vertical flange 16 is secured to the inner face of the upper ring 11 in any suitable manner such as by welding or the like, and the horizontal flange has an opening 18 therethrough for receiving the hook 15 of an associated arm 14.

A cover for the frame A is generally indicated at D and comprises an outer layer or facing 19 and an inner layer or lining 20 which are joined together in any appropriate manner as by a row of stitching 21. The cover D is adapted to be folded upon itself along a fold line 22 in the outer layer 19. Three spaced apart slits or eyelets 23 are formed in the outer layer 19 between the row of stitching 21 and the fold line 22 for permitting the horizontal flanges 17 of the brackets C to extend through the outer layer 19 when the cover is mounted on the frame A. A row of stitching 24 joins the free side edge portions 19a of the outer layer 19 and the free side edge portions 20a of the lining 20, respectively.

One tooth element 25 of a conventional zipper type fastener generally indicated at E is attached to the free end portion of the outer layer 19 and the other tooth element 26 of the fastener is attached to the free end portion of the lining 20. The slider 27 of the zipper fastener is carried by the element 25. Braid trimming, or the like, 28 may be attached in any suitable manner to the free end portion of the outer layer 19 to conceal the zipper fastener E. A similar braid trimming 29 may be attached to the outer face of the outer layer 19 just below the fold line 22.

In the use of the device, if it is desired to mount the cover D on the frame A, the fastener E will be moved to open position to afford access to the

space 30 between the outer layer 19 and the lining 20 and the hanger B will be removed from the frame A by exerting a downward force on the arms 14 to remove the hooks 15 from the openings 18 in the brackets C. The cover D will be slipped downwardly over the upper ring 11 of the frame in much the same manner as a pillow case is slipped over a pillow. The downward movement of the cover will be arrested by the engagement of the portions of the outer layer 19 adjacent the fold line 22 with the upper ring 11 at which time the zipper elements 25 and 26 will meet at the base ring 10 so that the zipper elements can be interlocked by the slider 27 to maintain the outer layer 19 and the liner 20 in properly stretched position on the frame A. As shown in Figures 1 and 4 of the drawings, the outer cover 19 will extend downwardly a short distance on the inner side of the frame to present a pleasing appearance to the eye of the observer. The rings 10 and 11 and the vertical bars 12 will be disposed in the space 30 so that they are completely concealed by the cover.

The horizontal flanges 17 of the brackets C will be received by and extend through the slits of the cover D so that the cover may be applied to and removed from the frame A easily and without mutilating the cover or frame. This arrangement will also help to anchor the cover in its proper position on the frame. The hanger B will then be mounted on the frame A by inserting the hooks 15 of the arms 14 upwardly into the openings 18 in the horizontal flanges 17 of the brackets C from beneath the flanges 17. The distance of the upper portion of each hook 15 from the point of attachment of its arm 14 to the hub 13 is slightly less than the distance between this point of attachment and the adjacent wall of the associated opening 18 of the horizontal flange as each hook 15 is inclined upwardly and inwardly towards the hub 13. Such an arrangement will cause the hooks 15 to snap into their respective openings 18 and to frictionally engage said adjacent wall of the opening 18 to securely and yet removably hold the hanger B in its mounted position on the frame.

In order to remove the cover D the steps are reversed, that is, the hanger will be first removed, the zipper then opened and the cover slipped upwardly off the frame A. It will be noted that the cover D is a self-contained unit capable of maintaining itself upon the frame in the proper tightly drawn down position without any extraneous assistance as the fastening means is mounted entirely upon the cover and not having any part thereof on the frame.

The material for the cover may be cut in length to allow for pleated effect and does not entail any detailed pattern as any looseness in the material can be gathered in at top when sewing to lining and at bottom when attaching zipper. This cover can be completely made by machine sewing, including braid trimming, before putting on frame, thus cutting cost of labor. The elimination of tape binding which is used on hand sewn shades cuts the cost of material and labor.

The outer layer 19 may be of any desired color scheme and design and the lining may be of a similar or a contrasting color to augment the beauty of the lamp shade.

It is obvious that various changes and modifications may be made in the details of construction and design of the above specifically described em-

bodiment of this invention without departing from the spirit thereof, such changes and modifications being restricted only by the scope of the following claims.

What I claim is:

1. An improved lamp shade comprising a frame having a base ring, an upper ring, and a plurality of angularly spaced apart connecting bars having their opposite end portions attached to said rings, a cover capable of being removed and reused without being mutilated or defaced comprising an inner layer and an outer layer having overlapping edge portions joined by stitches, the free vertical edge portions of each layer being secured together by stitches, said layers providing a space therebetween which receives said rings and said connecting bars, and zipper means for detachably connecting the other adjacent edges of the layers together after the layers have been disposed about said rings and bars and comprising a row of teeth carried by said other adjacent edge of one layer, a second row of cooperating teeth carried by said other adjacent edge of the other layer and a slider for detachably interlocking said teeth.

2. An improved lamp shade comprising a frame having a base ring, an upper ring, and a plurality of angularly spaced apart connecting bars having their opposite end portions attached to said rings, a plurality of angularly spaced apart brackets each comprising a vertical flange secured to said upper ring and a horizontal flange having an opening therein, a hanger comprising a hub and a plurality of arms radiating therefrom, a hook carried by the free end portion of each arm and adapted to be frictionally received by the opening in one of said brackets, a cover capable of being removed and reused without being mutilated or defaced comprising an inner layer and an outer layer having overlapping edge portions joined by stitches, the free vertical edge portions of each layer being secured together by stitches, said layers providing a space therebetween which receives said rings and said connecting bars, and zipper means for detachably connecting the other adjacent edges of the layers together after the layers have been disposed about said rings and bars and comprising a row of teeth carried by said other adjacent edge of one layer, a second row of cooperating teeth carried by said other adjacent edge of the other layer and a slider for detachably interlocking said teeth, said inner layer having adjacent said upper ring a plurality of angularly spaced apart slits through which extend the horizontal flanges of said brackets so that the openings in the horizontal flanges are exposed for the reception of said hooks without mutilating the cover.

KATHERINE A. STROSCHEN.
